UNITED STATES PATENT OFFICE.

HENRY J. HEIDER, OF CARROLL, IOWA.

STEPLADDER.

1,401,470.

Specification of Letters Patent. Patented Dec. 27, 1921.

Application filed June 30, 1921. Serial No. 481,714.

To all whom it may concern:

Be it known that I, HENRY J. HEIDER, a citizen of the United States, residing at Carroll, in the county of Carroll and State 5 of Iowa, have invented new and useful Improvements in Stepladders, of which the following is a specification.

This invention relates to step ladders, and especially to the means for securing the 10 steps to the supporting bars or legs.

The object is to provide means for embracing the ends of the step to prevent any tilting motion of the same and at the same time to engage the opposed faces of the 15 supporting bars or legs in such manner as to prevent forward or backward movement of the step with relation to the legs.

A further object is to provide such means in the form of a metal casting of 20 simple construction, easily and cheaply manufactured, said casting being adapted to embrace the leg and the step in the above manner and to permit of the application of a truss rod beneath the step for binding the 25 legs against the ends of said step with the castings interposed therebetween and also to permit of the passage of nails or other similar fasteners through the said legs and into the ends of the steps.

30 A full and complete understanding of the invention may be obtained from a consideration of the following detailed description, taken in connection with the accompanying drawing forming a part of this specification, 35 it being understood that while the drawing shows a practical form of the invention, the latter is not confined to strict conformity therewith, but may be changed or modified so long as such changes or modifications 40 mark no material departure from the salient features of the invention, as specifically pointed out in the appended claim.

In the drawing, in which similar reference characters designate corresponding parts 45 throughout the several figures:

Figure 1 is a perspective view of a ladder having the improved fastening means applied to the steps thereof.

Fig. 2 is an enlarged front elevation, 50 partly in section, of one of the steps of the ladder and the fastening means therefor.

Fig. 3 is a detail horizontal section through one leg and the adjacent end of the step, with the fastener interposed therebetween.

Fig. 4 is a vertical section of the same.

Fig. 5 is an elevation of the fastener.

Referring to the drawing, there is shown, in Fig. 1, a complete step ladder including supporting bars or legs 1, brace bars or 60 props 2, spreading means 3 of any desired construction and including the usual shelf or platform 5 to which the legs 1 and props 2 are hingedly connected, as indicated at 6 or in any other well known and desirable 65 manner, the brace bars or props 2 being suitably connected together to cause their simultaneous swinging action, as by the crossed bars 7, which also serve to hold them in proper spaced relation at their lower 70 ends.

The ladder as thus far described is of an old and well known form of construction and may be of any other form, the present invention reciting the means, as has been 75 stated, of attaching the steps to the aforesaid legs to position the same in a horizontal plane when the ladder is set up for use with the legs in an inclined position and to brace the step and maintain the same 80 rigidly between the legs in a manner to support great weight without danger of slipping or breaking.

The invention comprises a supporting bracket 8 composed of cast steel or other 85 suitable metal and formed to provide an elongated base plate 9 of a width slightly greater than the thickness of the step 10 of the ladder and substantially co-extensive in length with the width of the said step, the 90 front and rear edges 11 of the base member being arranged at an angle to the top and bottom edges, as clearly shown in Fig. 5, so as to conform to the horizontally disposed step and the inclined legs, when the ladder 95 is set up for use, as will be clearly understood.

Along the top edge of the base plate 9 there is provided an inwardly directed flange 12 extending from the front to the rear end 100 of the plate and along the lower edge, the said plate is provided with spaced flanges 13, directed inwardly and extending from the front and rear edges of the plate to a point adjacent to the center thereof, the 105 flanges 12 and 13, which are formed integrally with the base plate 9, being adapted to receive the adjacent end of the step 10 between the same, as clearly shown in Fig. 4 of the drawing.

Extending from the opposite or outer face 110 of the base plate 9 and along the inclined

front and rear edges of the same, are outwardly directed flanges 14, between which is adapted to be fitted the inclined legs 1, the inner face of which fits flat against the outer face of the base plate 9 and whose front and rear edges snugly bear against the said outer flanges 14 so as to prevent any possible tilting motion of the plate against the said leg, while the aforesaid flanges 12 and 13 prevent any like action of the step with relation to the bracket.

Between the inner lower flanges 13, the base plate 9 is provided with a downwardly directed extension 15 of even thickness with the said base and having, midway between the said flanges, an opening 16 preferably rectangular in shape, and arranged in alignment with said flanges, while the body of the base plate 9 is provided with a pair of spaced openings 17 located equal distances from the front and rear edges 11 of the plate and midway between the upper and lower, inner flanges 12 and 13 respectively.

When the brackets 8 are properly applied with the step 10 fitting between the flanges 12 and 13, at each end, and the legs 1 positioned between the outwardly extending flanges 14, a nail 18 is driven from the outside through the leg 1 in alignment with each of the openings 17 of the base plate 9, through which the said nails pass and into the end of the step 10.

In order to further strengthen the structure and assist the nails in sustaining the weight to which the step may be subjected, a truss rod 19 is employed, the same being located underneath the step 10, from which it is spaced, at the center thereof, by a block 20, formed of wood preferably and secured to the under side of the step by suitable nails, the outer ends of the truss rod rising upwardly from the block to lie immediately beneath the step and in line with the lower face thereof and traversing the opening 16 and suitable apertures 21 previously formed in the legs 1 of the ladder.

The terminals of the truss rod 19 are threaded for the reception of nuts 22 located at the outer sides of the legs 1 and preferably having washers 23 interposed between them and the legs to prevent the wearing of the wooden leg when the nuts are turned up to tighten the truss rods in a manner to bind the legs between the flanges 14 of the bracket

and in turn to hold the latter against the ends of the steps 10, as will be clearly understood.

A straight longitudinal pull is exerted upon the step 10 by the truss rod 19 by reason of the terminals of the latter being so nearly in alignment with the same and it will be seen that the flanges 14 located against the outer or front edges of the legs 1 help to sustain the weight on the step and thus relieve the strain on the nails and the truss rod, by reason of the inclination of the said legs when the ladder is set up for use.

From the foregoing it will be seen that a simple and cheaply manufactured bracket has been provided for use in connection with step ladders to secure the steps thereof to the legs of the same and that the said bracket may be easily and quickly applied in position to form a strong and durable structure, provision being made for the application of the fastening nails and the truss rod which latter member greatly strengthens and prolongs the life of the ladder.

What is claimed is:—

A bracket for supporting the step of a step ladder comprising an elongated base plate having upper and lower, inwardly directed horizontal flanges arranged along the upper and lower edges thereof and adapted to receive the adjacent end of the step, the lower flange comprising two spaced sections, said base having a lower opening located between the said sections and a pair of spaced openings located between the upper and lower flanges, and outwardly directed inclined flanges located at the front and rear edges of the base plate and adapted to receive the inner face of the inclined leg of the ladder between the same and to bear against the inclined front and rear edges thereof, nails traversing the leg of the ladder and the spaced openings intermediate the inner flanges and entering the end of the step, and a truss rod reaching from end to end of the step below said step and traversing the lower opening in the base plate between the spaced sections of the lower flange and the leg of the ladder, and means for tightening the truss rod.

In testimony that I claim the foregoing as my own, I have hereunto affixed my signature.

HENRY J. HEIDER.
